W. T. BARRATT

STOP MOTION MECHANISM WITH TRIPPER DEVICE

Filed July 10, 1923

UNITED STATES PATENT OFFICE.

WILLIAM T. BARRATT, OF BENNINGTON, VERMONT.

STOP-MOTION MECHANISM WITH TRIPPER DEVICE.

Application filed July 10, 1923. Serial No. 650,568.

To all whom it may concern:

Be it known that I, WILLIAM T. BARRATT, a citizen of the United States, residing at Bennington, in the county of Bennington and State of Vermont, have invented new and useful Improvements in Stop-Motion Mechanism with Tripper Devices, of which the following is a specification.

This invention relates to improvements in stop motion mechanisms for machines in which a strand or strands of yarn are employed in the manufacture of fabrics.

The particular embodiment of my invention hereinafter set forth in the specification and embodied in the claims is especially adapted for use in connection with knitting machines.

The object of the invention is to provide a stop mechanism which will stop the machine when the yarn which is fed into the machine has a bunch or enlargement thereon and is subjected to excess tension or undue strain, for example, when the strand of yarn becomes knotted or has kinks or enlargements therein.

The object of the invention is further to provide a stop mechanism which will collect upon a tripper device loose lint or waste from the yarn and after a certain amount of said lint or waste collects upon the tripper device the same will be actuated by the yarn to stop the machine.

Another object of the invention is to provide a tripper device which will act with very little friction on the yarn to operate a stop mechanism.

The object of the invention is further to provide a series of tripper devices each of which constitutes a guide for a strand of yarn and each of which will act to stop the machine independently of the other tripper devices.

It will be understood, therefore, that the main object of the invention is to provide a very sensitive tripper device to actuate the stop motion, whereby a machine employing the lightest and frailest kinds of yarn may be stopped when the yarn has kinks, bunches or enlargements therein, said tripper device acting to remove loose lint or waste from the yarn while it is feeding to the machine and which is capable of operating to actuate the stop mechanism to stop the machine when a certain amount of lint or waste has gathered thereon.

Other objects and desirable results to be

attained will be more fully hereinafter set forth in the specification.

The invention consists particularly in a tripper device and the manner in which it operates to cause a stop mechanism to be actuated to stop the machine.

This invention, in so far as the principal part of the stop mechanism is concerned, is substantially the same as the mechanism disclosed in my United States Letters Patent No. 1,461,172, patented July 10, 1923 and in many respects the stop mechanism is similar to the stop mechanism patented by me No. 1,173,244, patented February 29, 1916 and No. 1,186,645, patented June 13, 1916, to which Letters Patent, reference may be had with relation to the details of the stop mechanism.

To these ends and others hereinafter appearing in the specification, the invention consists in the combination and arrangement of parts set forth in the following specification and particularly pointed out in the claims thereof.

Referring to the drawings:—

Figure 1 is a plan of a portion of the stop mechanism of my invention, illustrating the tripper device and the portion of the stop mechanism immediately connected therewith, the same being broken away to save space in the drawings.

Fig. 2 is a sectional elevation taken on line 2—2, Figure 1, the same being broken away to more clearly illustrate the invention.

Fig. 3 is an enlarged side elevation partly in section and broken, of one of the tripper arms shown in connection with a rock shaft upon which it is pivotally mounted.

Fig. 4 is a perspective view of one of the tripper arms in reversed position.

Like numerals refer to like parts in the several views of the drawings.

In the drawings, 10 is the frame of the machine. 11 is a rotary shaft to which are fastened toothed discs 12 and 13 which constitute rotary stop members. 14 and 15 are oppositely disposed brackets. The bracket 14 has a rock shaft 16 pivotally mounted thereon and at one end of said shaft an arm 17 is fast thereto and projects upwardly, terminating in a yarn guide 18. This arm is provided with a slidably adjustable weight 19 which is held in adjusted position by a spring 20, Fig. 2.

A stationary yarn guide 21 is positioned above the yarn guide 18 and is fastened to

the bracket 14. Another yarn guide 22 is positioned below the yarn guide 18 and is mounted on a bracket 23 which is adjustably fastened to the bracket 14, so that the yarn guide 22 can be adjusted toward and away from the yarn guide 18 to increase or diminish respectively the tension upon the yarn 24, which yarn extends from a bobbin, not shown in the drawings, and passes through a stationary yarn guide 25 fast to the frame of the machine, through the yarn guides 22, 18 and 21 and thence passes to the machine where it is guided to the needles in the usual manner.

15 The arm 17 is normally, that is, when the yarn is passing through the yarn guide 18 under tension during the operation of the machine, positioned at a slight angle to a vertical plane containing the axis of the rock shaft 16. It is prevented from assuming at any time a vertical position by abutting against the bracket 23, so that when the yarn 24 breaks, the arm 17 and yarn guide 18 will tip downwardly and bring a locking arm 26, which is fast to or forms a part of the rock shaft 16, into the path of the rotary stop member 13 and the arm 26 will abut against a normally stationary stop 27. The arm 26 will thus act as a locking means, 30 which stops the rotation of the rotary stops 12 and 13 and the shaft 11 to which they are fastened. When this occurs, the stop mechanism of the machine will be operated to throw out the clutch and stop the machine, 35 as set forth in said Letters Patents No. 1,461,172 and No. 1,173,244.

The yarn 24', Fig. 2, is led from a bobbin, not shown in the drawings, through yarn guides 25', 22', 18' and 21', Fig. 2, to the needles of the machine, the yarn guide 18' being supported upon an arm 17' which extends upwardly from a rock shaft 16' pivotally mounted on the bracket 15 and provided, at the opposite end thereof from that to which the arm 17' is attached with a laterally extending arm 26', which is adapted to be engaged by the rotary stop member 12 when the yarn 24 breaks and to abut against the normally stationary stop 27, thus stopping the machine, as hereinbefore described.

The operation of the yarn guide 18' and its associated parts is the same as that of the yarn guide 18 hereinbefore described, 55 the only difference being that the arm 26' projects in the opposite direction from that of the arm 26.

The number of bobbins and the number of yarn guides and rotary stops may be increased as desired and all operate as hereinbefore described.

The mechanism hereinbefore described is substantially the same as that set forth in said United States Letters Patent No. 1,461,- 65 172.

The novel tripper device and its connections with the stop mechanism will now be described. A rock shaft 28 is pivotally mounted on brackets 29 and 29' fast to a bar 30, which in turn is fastened to the frame 10. Said rock shaft has a rocker arm 31 fast to one end thereof and having a pin 32 projecting laterally therefrom and forming in effect a part thereof. When in its normal position the pin 32 is out of contact 70 with the rotary stop member 12 but can be thrown into engagement therewith by the rock shaft 28 when the same is rocked by any one of a series of tripper arms 33. All of these tripper arms are alike but only one is 80 shown in the drawings, the same consisting of a piece of flat thin metal which is provided with a hole 34 connected by a slot 35 to one end of said tripper arm. The other end of said tripper arm is bent to form an 85 eye 36 in which is provided a slot 37. The eye portion 36 of the tripper arm is loosely mounted upon the rock shaft 28 and a pin 38 fast to said rock shaft projects through the slot 37, as shown in Figures 2 and 3. 90 The tripper arm 33 normally rests upon a stop rod 39 fastened at its opposite ends to the brackets 29 and 29' and when so resting the pin 38 will be located in said slot adjacent the inner end thereof, as illustrated in 95 Fig. 3.

It will be understood that there are pivotally mounted upon the rock shaft 28 a plurality of these tripper arms 33 and each one is operative independent of the others, 100 that is, if the tripper arm, as shown in Figs. 2 and 3, is in its normal position and resting against the stop rod 39 and a kink or enlargement in the yarn, or an accumulation of lint on the yarn, causes the yarn to lift the 105 tripper arm 33, which it will do as soon as the free passage of the yarn through the hole 34 is restricted, then the tripper arm 33 will be lifted from the position shown in full lines Fig. 2 to the position shown in 110 dotted lines therein and the inner end of the slot 37 will abut against the pin 38 and rock the rock shaft 28. At the same time the pins 38 for the other tripper arms will move in their respective slots 37 and their 115 respective tripper arms 33 will remain stationary. The object of this construction is to render the device as sensitive as possible and to give the yarn as little work as possible when it rocks the rock shaft 28.

When the rock shaft 28 is rocked, as hereinbefore described, the rocker arm 31 will rock with it from the position shown in full lines, Fig. 2, to the position shown in dotted lines therein and the pin 32 on said rocker arm and which forms in effect a part thereof is then brought into the path of the teeth 12' of the rotary stop member 12. One of said teeth will then engage the pin 32 and the rotation of the toothed disc or rotary 130

stop member 12 will be stopped, together with the rotation of the shaft 11, and the stop motion will then operate as described in said Letters Patent No. 1,461,172, to stop 5 the driving shaft of the knitting machine and thus the parts driven by said driving shaft will come to a stop.

Another series of tripper arms in connection with the yarn 24' are employed to 10 actuate the stop mechanism. One of these tripper arms 33' is illustrated in Figures 1 and 2, and the operation thereof is the same as hereinbefore described in relation to the tripper arms 33, except that they are loosely 15 mounted in a like manner upon a rock shaft 28' and rest when in their normal position upon a stop rod 39'. The rock shaft 28' has an arm 40 fast thereto which is connected by a link 41 to another rocker arm 20 42 which is pivoted to rock on a pin 43 fast to the bracket 29'. This rocker arm has a pin 44 fast thereto which is brought into alignment with the teeth 12' of the rotary stop member 12 when the arm 42 is rocked 25 by the arm 40 and one of the tripper arms 33'.

It will therefore be seen that when any one of the tripper arms 33' is rocked by an enlargement or kink or by accumulated 30 lint on its respective yarn 24', said tripper arms will rock the rock shaft 28' and will move the rocker arm 40 from the position shown in full lines to the position shown in dotted lines, Fig. 2, whereupon the rocker 35 arm 42 will be rocked on its pivot 43 to bring the projection 44 thereon into the path of the teeth 12' of the rotary stop member 12. When this occurs the rotary stop member will be stopped, together with the shaft 40 11 and the stop motion mechanism will be operated to stop the knitting machine as described in said United States Letters Patent 1,461,172. The stop motion mechanism will also be actuated to stop the 45 machine when the yarn runs out, or when it breaks, by the arm 17, rock shaft 16 and arm 26, or by the arm 17', rock shaft 16' and arm 26', all in the manner set forth in said United States Letters Patent 1,461,172.

50 It will therefore be seen that the stop motion mechanism will be operated to stop the knitting machine, either when the yarn breaks or when it runs out, or when there is an enlargement or kink therein, or when 55 lint accumulates on the tripper arms the stop motion will be actuated to stop the machine by one of the tripper arms of the mechanism hereinbefore described, whereby said stop mechanism is thrown into 60 operation.

It is desirable that the tripper arms should be capable of a slight angular movement before they operate to rock their respective rock shafts and to attain this end the inner 65 end of the slot 37 does not engage the pin

38 when the tripper arm is in the position illustrated in Fig. 3, or in its normal position, but will engage said pin when the tripper arm has been moved by the yarn through a predetermined angle. By this construction 70 a slight angular movement of the tripper arms is possible without the machine being stopped by such movement.

I claim:—

1. A stop motion mechanism for a knitting machine having, in combination, a rotary stop member, a rock shaft, a rocker arm fast thereto, a tripper arm loosely mounted to swing on said rock shaft, a projection on said rock shaft adapted to be 75 engaged by said tripper arm, whereby said rocker arm may be moved into interlocking engagement with said rotary stop member and the rotation of said rotary stop member stopped and mechanism actuated by the 80 stopping of said rotary stop member constructed and arranged to stop the rotation of the driving shaft of said knitting machine.

2. A stop motion mechanism for a knitting machine having, in combination, a rotary stop member, a rock shaft, a rocker arm fast thereto, a tripper arm loosely mounted to swing on said rock shaft, a projection on said rock shaft adapted to be 90 engaged by said tripper arm after it has been rocked by the yarn through a predetermined angle, whereby said rocker arm may be moved into interlocking engagement with said rotary stop member and the rotation of 95 said rotary stop member stopped and mechanism actuated by the stopping of said rotary stop member constructed and arranged to stop the rotation of the driving shaft of said knitting machine.

3. A stop motion mechanism for a knitting machine having, in combination, a rotary stop member, a rock shaft, a rocker arm fast thereto, a plurality of tripper arms mounted on said rock shaft each constituting a yarn guide, a series of projections on said rock shaft, each of said projections projecting into a slot provided in each of said tripper arms respectively, whereby each of said tripper arms may be rocked by 110 its respective yarn to rock said rocker arm into interlocking engagement with said rotary member independently of the other tripper arms and whereby the rotation of said rotary stop member may be stopped, and mechanism actuated by the stopping of said rotary stop member constructed and arranged to stop the rotation of the driving shaft of said knitting machine.

4. A stop motion mechanism for a knitting machine embodying a rock shaft, a plurality of tripper arms loosely mounted to swing on said rock shaft, and a series of projections on said rock shaft projecting into slots in said tripper arms, whereby each 125

of said tripper arms may be actuated by its respective yarn to rock said rock shaft independent of the other tripper arms of said series.

5. A stop motion mechanism having, in combination, a rotary stop member, a rock shaft, a rocker arm 40 fast thereto, another rocker arm 42 pivotally mounted adjacent to said rotary stop member, a link connecting said rocker arms 40 and 42 to each other, a tripper arm mounted on said rock shaft and constituting a yarn guide, whereby said rocker arm 42 may be rocked into interlocking engagement with said rotary stop member and the rotation of said rotary stop member may be stopped and mechanism actuated by the stopping of said rotary stop member constructed and arranged to stop the rotation of the driving shaft.

6. A stop motion mechanism having, in combination, a rock shaft, a plurality of tripper arms constituting yarn guides, loosely mounted to swing on said rock shaft, projections on said rock shaft each adapted to be engaged by its respective tripper arm when said tripper arm is rocked by its respective yarn on said rock shaft and mechanism adapted to be set in operation by said rock shaft, constructed and arranged to stop the rotation of the driving shaft of 20
25
30 said knitting machine.

In testimony whereof I have hereunto set my hand in presence of two subscribing witnesses.

WILLIAM T. BARRATT.
